ELECTRICALLY OPERATED INDEXING AND PRE-
SETTING MEANS FOR A CLOCK OR LIKE
MECHANISMNicholas J. Hickly, Whitehall, Pa., assignor to Pennwood
Numechron Company, Pittsburgh, Pa., a corporation
of PennsylvaniaFiled Feb. 29, 1960, Ser. No. 11,680
2 Claims. (Cl. 58—26)

This invention is for a clock or similar mechanism, and is for a multiple dial direct-reading clock or like mechanism in which the numerals indicating increments of time or motion are read directly from left to right on the peripheries of a series of dials.

In Greenawalt Patent No. 1,990,645 dated February 12, 1935, there is disclosed a direct-reading clock having a succession of dials with numerals on the periphery, and each revolution of a dial at the right-hand side of the series moves the next dial to the left one increment, and when that dial in turn rotates one revolution, the next dial is moved one increment. In this mechanism the right-hand dial has ten faces with each face bearing a numeral, the numerals reading from 0 to 9. The next dial has six faces with numerals reading from 0 to 5. The last dial to the left has twelve faces reading from 1 to 12. The transmission of motion from one dial to another is dependent, among other things, on the fact that the dials are of different diameters so that a motion-transmitting projection on one dial moves in an arc that is not concentric with the element of the adjacent dial to which it transmits movement.

This mechanism is entirely satisfactory for a simple twelve-hour clock. However, it is unsatisfactory for a twenty-four hour clock, for example, since the hour dial cannot well be much larger in diameter than the corresponding dial of a twelve-hour clock. Therefore, to provide numbers reading from 1 to 24, the numerals are crowded and small as compared to the numerals on the minute dials. Again, in some industrial applications, a continuous record running into hundreds of hours may be desirable, and a mechanism like that shown in the Greenawalt patent is unsuited for such purpose. Also, for purposes where counting is to be done in intervals—say for example ten or fifteen-second intervals—a mechanism as shown in the Greenawalt patent is unsuitable. There are, of course, clock-type mechanisms, like odometers, where the dials are connected through gearing, and each dial to the left moves one-tenth of a rotation with each full revolution of the next dial to the right. Such positively-gearied devices lack flexibility for many operations or locations.

With a gear train type of movement, resetting generally requires some operation of turning the dials ahead until they all read zero. This is often a relatively slow procedure, or it may not always be desirable. For example, in traveling west, one may want to change to an earlier time zone, say from 3:45 to 2:45. It is awkward to turn all of the dials ahead to zero and then advance them to 2:45. Various other situations arise where independent movements of the dials may be desirable.

The present invention has for its principal object to provide a clock or similar mechanism having multiple dials, in which each dial has its own electromagnetic means for rotating it.

A further object of my invention is to provide a multiple dial clock or counter in which a predetermined travel of one dial sends an electric impulse to energize the electromagnetic means for rotating a succeeding dial.

A further object of my invention is to provide a multiple dial clock with an electromagnetic means for rotat-

2

ing some of the dials, and wherein there are selectively operable means for independently setting each dial.

A further object of my invention is to provide a simple and unique clock or counting mechanism.

These and other objects and advantages are secured by my invention which may be more fully understood by reference to the accompanying drawings, in which:

FIG. 1 is a top plan view of a mechanism embodying my invention, the usual housing or casing being omitted;

FIG. 2 is a front elevation of the mechanism shown in FIG. 1;

FIG. 3 is a transverse vertical section in the plane of line III—III of FIG. 1; and

FIG. 4 is a schematic wiring diagram showing one wiring circuit for the apparatus.

In the drawings, 2 designates a base having an upright support 3 secured thereto near one end thereof. Carried on one face of this support is a synchronous motor of the type commonly used in electric clocks, and which, together with a reducing gear, is encased in a housing. The motor and gear assembly is designated 4. There is a shaft 5 driven by the motor which passes through the upright 3, and it has an eccentric cam 6 on its outer end.

There is a second upright support 7 on the base near the other end. There is a fixed shaft 8 mounted in the supports 3 and 7. Loose on the shaft 8 for independent rotation is a series of similar dials or drums 9, 9a and 9b. Each drum has a central hub portion 10 through which the shaft 8 is passed, a web portion 11 and a rim 12 which is wider than the web. The rim 12 is preferably of polygonal contour with a number of equal flat faces on which numbers are printed. The dials or drums are desirably molded of plastic, and while they are shown as being polygonal, they might just as well be cylindrical.

Projecting from one edge of each dial is a series of equally-spaced pins 13 that may be of metal molded into the plastic, and one pin is located at each corner of the polygon. A spring 14 is shown around the shaft 8 between the upright 7 and the hub of the dial 9b for yieldably urging this dial toward the right, and since the hub of one dial contacts that of an adjacent dial, this pressure is transmitted to all of the dials.

There is a bracket 15 secured to the base back of the dials. It has a foot portion 15a secured to the base, a vertical web 15b, and a rearwardly-projecting top flange 15c. Mounted on the top of flange 15c is a series of forwardly-projecting arms 16. Each arm 16 supports a micro-switch of similar construction, the number of micro-switches being equal to the number of dials, and they are designated 17, 17a and 17b.

Micro-switch 17 is located in a position to be operated by the rotation of cam 6. Dial 9 has a pin 18 projecting from its periphery, so that once each revolution it engages micro-switch 17a. Dial 9a has a similar pin 18a on its periphery to engage and trip micro-switch 17b. While I have shown three dials and three micro-switches, there may be many more, the number of switches corresponding to the number of dials, and each dial would have a switch-tripping element or pin or cam similar to 18, except the last dial to the left, where it is not needed.

Secured to the under side of the bracket flange 15c are several solenoids corresponding in number to the number of dials or drums, there being one solenoid to the rear of each drum. These are designated 19, 19a and 19b, corresponding to drums 9, 9a and 9b respectively.

Each solenoid has an armature 20 to which is attached a horizontal bar 21, preferably of aluminum or plastic, to reduce weight. One bar extends forwardly from each solenoid armature along the edge of one of the drums, the bar being of a width to have a working clearance between two pins 13 on the edge of the dial which it oper-

ates, and in its normal extended position this engagement of two pins of each dial with the upper and lower edges of the bar holds the dial against free rotation or over-travel. The bar has a downwardly and forwardly-extending portion 23 at its outer end with a horizontal extension 24 forming its outermost portion. Each portion 24 has one end of a tension spring 25 attached thereto, the other end of each spring being anchored to a fixed post 26 secured to the base, there being one anchor post 26 for each bar 21. The springs serve to yieldably resist movement of the armatures on which they are carried to their retracted positions, and to return the bars 22 to their normal extended position.

The downwardly and forwardly-sloping edge of the bar is cut away to provide a camming surface 23a so positioned that as the bar 21 moves to the right as viewed in FIG. 3 under the influence of the solenoid, such surface strikes that pin 13 which is immediately under the bar, tending to rotate the drum in a clockwise direction. The bar 21 has a groove 22a transversely across that face of the bar which confronts the pin-carrying edge of the drum. The groove 22a is generally of chevron-like shape, with reversely-sloping edges 22b and 22c at the forward edge of the groove. Before the bar moves to the right sufficiently for the edge 23a to start moving the under pin down, the bar will have moved to a point where the pin at the top edge of the bar is over the slot, so that the disk may rotate in a clockwise direction as camming surface 23a, moving to the right, exerts downward pressure on the lower of the two pins in question. When the solenoid armature has completed its stroke to the right, the upper pin will have moved in an arc to the point marked 22' in the groove. Then, as the bar 21 moves to the left under the action of the spring 25, inclined camming surface 22b will engage this upper pin, now moved half way down the slot, completing one full increment of movement of the dial, and the parts will again be in the position shown in FIG. 3. Thus the first half of an increment of rotation is effected by the retracting movement of the bar 22, and the second half by the return movement, and each drum is positively locked against free rotation or over-travel.

In FIG. 4 I have shown a wiring diagram for the apparatus in which lines 30 and 31 are current supply lines. The motor is designated 4, and is connected across these lines. A branch line 32 from line 30 is connected to one side of each solenoid, which are here also designated 19, 19a and 19b. From each solenoid there is a wire 33 leading to the respective micro-switches 17, 17a and 17b. Wire 34 leads from switch 17 to wire 35 to one contact 36 of a two-contact push-button switch 37. The switch 37 is biased to normally close a circuit with contact 36. The switch 37 may be pushed down to engage contact 38 and open the circuit to contact 36. Switch 37 is connected through wire 39 to the other line wire 31. Contact 38 is connected to wire 39 that shunts around the micro-switch 17 to wire 33.

Wire 35 also connects to a similar push-button switch 40 having two contacts 41 and 42. The switch is biased to normally close a circuit to contact 41, and this contact is connected to a wire 43. Wire 44 connects the micro-switch 17a to wire 43, and there is a shunt circuit around the micro-switch provided from contact 42 to wire 33. Wire 43 is connected to a third double contact push-button switch 45 having contacts 46 and 47, and the switch is biased to normally close a circuit through contact 46 with wire 48. Branch wire 49 connects 48 with micro-switch 17b. A shunt circuit 50 is provided around micro-switch 17b from contact 47 to wire 33 for the third solenoid. This arrangement may be repeated for as many dials as may be used, and is not restricted to the three which are shown.

In operation, rotation of the eccentric cam 6 momentarily closes micro-switch 17, closing a circuit through the micro-switch and the normally closed push-button switch

37 through the solenoid 19 to the current supply lines 30 and 31. Therefore each revolution of cam 6 rotates drum 9 through one increment. When pin 18 on this dial moves past micro-switch 17a, an impulse is sent through solenoid 19a to rotate dial 9a one increment. Likewise, when pin 18a on dial 9a moves past micro-switch 17b, an impulse is sent through solenoid 19b to rotate dial 9b through one increment.

Three push-buttons 37a, 40a and 45a are shown in the base in FIG. 1 for separately operating the switches 37, 40 and 45. By pushing down on any button an impulse may be sent through the selected switch through the shunt circuit to a selected solenoid to rotate a selected drum, but since the normally closed contacts of the several switches are in series, the circuit to the left of the push-button so operated is opened, so that the movement of one dial then is ineffective to move any other dial. Thus the position or setting of each dial may be effected without changing any other dial. By pushing the selected button a number of times in succession, a selected dial may be rotated through a corresponding number of increments.

There is provided therefore a multiple dial clock or counting mechanism in which each dial is independently moved by an electric impulse generated by the motion of a preceding dial, with no gearing between dials, and the ratio of movement of one dial to another may be varied by changing the number of pins 18 on any one dial. For example, if on dial 9 there were two pins 18 located 180° apart, dial 9a could rotate two increments for each rotation of dial 9, instead of only one. If a clock is to measure fifteen-second intervals instead of sixty-second intervals, it can readily be made to count such intervals. Also, instead of the cam 6 being turned by a synchronous motor, any other driving means may be substituted to count revolutions or cycles instead of abstract time.

While I have shown a mechanism having but three drums or dials, there may be provided any desired number within practical limits, and while all dials are here shown as being of the same size, they may be of different sizes, as in the aforesaid Greenawalt patent, for example. By having push-button switches with normally closed contacts in series and the normally open contact shunted around the micro-switch for the drum which it governs, any dial may be selectively moved or set without affecting any other dial.

While I have shown and described one specific embodiment of my invention, it should be understood that this is by way of illustration and that various changes and modifications may be made in the construction of the apparatus within the contemplation of my invention.

I claim:

1. A clock mechanism comprising a series of dials mounted for independent rotation in side-by-side relation, a series of electromagnets corresponding in number to the number of dials with one magnet for serving each dial, the magnets being supported alongside the dials, each magnet having an armature movable back and forth with relation to the dial which it serves, the armature being moved in one direction by the magnet and having a spring for moving it in the opposite direction, cooperating means on each armature and the dial which it serves for moving said dial through a predetermined arc with each cycle of movement of the armature and restraining it against movement greater than said predetermined arc and independently of the actuation of said armature, means for intermittently energizing the electromagnet at one end of the series to effect a cycle of movement of the armature thereof, said dial and each succeeding one in the series except the one at the opposite end of the series having a switch-operating element thereon, a switch for each succeeding electromagnet after the first positioned to be engaged by the switch operating means of the preceding dial during a selected cycle of movement of said preceding dial, a circuit for each switch and the electromagnet which it operates whereby each rotation of the first dial mo-

mentarily closes the switch and circuit for the electromagnet for the next dial to move its armature through a full cycle and each dial in turn similarly energizes the electromagnet for the next-succeeding dial, each circuit including a push button switch for selectively rotating each dial manually while de-energizing the circuits for any succeeding electromagnet in the order of their operational sequence in the series.

2. A clock mechanism of the class described comprising a dial, means for rotatably supporting the dial, the dial having a rim with a series of equally-spaced pins extending therefrom in a direction parallel with the axis of rotation of the dial, an electromagnet adjacent the dial, an armature for the electromagnet reciprocated in one direction by energizing the magnet, a spring for effecting return movement of the armature when the electromagnet is deenergized, an operating member connected to the armature and extending radially between two pins on said periphery of the dial and of a width to normally restrain the dial from rotation, said operating member having a rectangular bar the width of which is such as to have a working fit between two pins and which has a substantially V-shaped transverse groove in the face thereof that confronts the dial and a downwardly-extending inclined

cam surface thereon positioned radially of the dial inward of the groove, whereby the movement of said operating member by the electromagnet first brings that pin at the upper edge of said member over the groove to thereby permit the pin to enter the V-shaped groove, after which the inclined cam surface engages the pin below said member to push it down and thereby effect the first part of the full predetermined increment of movement of the dial and a wall of the V-shaped groove exerts a further camming action on the upper pin when the operating member is pulled back by the spring to advance said upper pin to the point previously occupied by the lower pin and a succeeding pin on said dial is then in the original position of the first-mentioned upper pin.
